UNITED STATES PATENT OFFICE

WILLIAM E. V. SHAW, OF MINNEAPOLIS, MINNESOTA

BUMPER RACK

Application filed April 28, 1930. Serial No. 448,132.

This invention relates to a device herein designated as a bumper rack, although the device is adapted for other uses. Among the objects are: to provide a load-supporting device which can be quickly attached to a bumper, and in which two or more of the devices can be attached to form luggage supports; to provide a device of this character which is formed from a single piece of metal bent upon itself to provide a trussed structure, which is attachable by frictional contact to a support; to provide such a device having means automatically operable to frictionally attach it to a support; and to further provide means for augmenting the frictional action of the last mentioned means.

Features of the invention include all the details of construction, along with the broader features.

20 Features and advantages will be set forth in the description of the drawings forming a part of this application, and in said drawings:

Figure 1 is a plan view showing two of the devices applied to the bumper of an automobile;

Figure 2 is a vertical cross section;

Figure 3 is a detail plan view;

Figure 4 is a vertical section corresponding to Figure 2, and showing a modified form;

30 Figure 5 is a vertical section corresponding to Figure 2, and showing a second modification;

Figure 6 is a perspective view showing a third modification; and

35 Figure 7 is a vertical section corresponding to Figure 2, and showing a fourth modification.

In this instance, two of the devices of the invention herein have been shown applied to the front bumper of an automobile. Refer-

40 ring to Figure 1, this bumper includes upper and lower front spring sections 1, and a rear spring section 2 connected at the ends as at

45 3 to the sections 1, and additionally connected at a midpoint as at 4. The bumper is secured in the usual manner to the automobile at 6.

In this case, two of the devices of this invention have been shown attached to the bumper and the devices are identical in structure.

50 The device is formed from a single piece of

strap metal bent to provide a generally triangular trussed structure best shown in Figure 2. This structure includes a load-receiving portion designated 10 adapted to assume a substantially horizontal position when the device is attached. The terminal portions of the strip are bent downwardly and toward one another respectively as at 11-12 to form the other two sides 13-14 of the triangle, and then are again bent upwardly as at 15-16 to provide two portions 17-20 opposed to form a clamp. The strap metal is springy, and element 20 tends constantly to move forcefully toward elements 17. As here shown these portions are substantially perpendicular to the portion 10, and the portion 17 is secured as at 18 to the portion 10. A trussed structure is thus formed. The up-turned portion 20 is not attached to the part 10, but has a reduced centrally arranged lug 21 which is slidably engaged in a slot 22, elongated in direction of the long dimension of the element 10. Motion of the element 20 in a direction perpendicular to its clamping motion is thus prevented. The frame is formed of springy material, and the opposed portions may be normally engaged. It will be noted at least one of the elements is free to yield in direction away from the other, and the element 20 does so yield when the device is forced over the bumper to the position shown in Figure 2. As shown in Figure 2, the front spring 1 of the bumper is really composed of upper and lower sections. Although the tension of the element 20 is ordinarily sufficient to secure the device in operative position, auxiliary means is provided both for preventing motion of the device in a vertical direction, and also for drawing the element 20 toward the element 17 to increase the clamping action. This means is provided by forming openings 26 in the elements 17 and 20, and by passing a bolt 27 through these openings, and providing a thumb nut 28 in threaded engagement with the bolt. For bumpers of the type shown, including upper and lower members 1, this auxiliary clamping means is arranged in the space between these members.

When a device is used on a bumper of the general type shown in Figure 2, which has front and rear portions 1 and 2, it sometimes happens that the parts are so related as to require the bending of the element 14 as at 25.

5 A structural modification is shown in Figure 4, wherein the upper terminal of the element 20 is bent horizontally as at 29. This is done because sometimes when attaching the rack to the bumper, or other support, and pressing downwardly to separate the elements 26 and 29 against their spring tension, the element 20 may be deformed due to pressure applied in direction of the arrow A. The part 29 is, therefore, arranged to act as a stop resting on the top of the edge of the bumper to prevent motion in the direction indicated. The end 30 of this element 29 is made as long as possible and extends into a recess 31 formed, for example, by curving the upper end of the element 17. The structure just described prevents withdrawal of the stop 29, when the device 28 draws element 20 toward element 17. A pin 32 traverses the element 29 and operates in the slot 33 substantially in the manner of the element 21.

30 Figure 6 shows a modification of the element of Figure 4, in which, instead of the pin 32, an equivalent device is formed by punching and turning up a portion of the stop 29^a as at 35.

35 Another modification is shown in Figure 5, in which the stop 29^b is provided with a down-turned terminal portion 36 to form a kind of hook which engages over the upper edge of the bumper section 1. With this construction, the stop cannot possibly be withdrawn. To provide for play between the end 36 of the stop and the element 17, this element is first bent outwardly as at 38 then upwardly as at 39 and then horizontally as at 40. A recess 41 is thus formed. The horizontal portion 40 is suitably secured as at 18 to the element 10. Play between the elements 36 and 39 is provided as described for the corresponding structure in Figure 4. The portion 36 is also spaced from the bumper or support 1. Pin 42 enters the slot 43. The hook-like structure of Figure 5 is advantageous where approximate thickness of the bumper is known, and of course the recess 45 formed by elements 20, 29^b and 36 is made sufficiently wide to receive supports of different thicknesses.

55 The present invention contemplates the very cheap production of a device of the nature described herein. As a matter of fact, the device is most economically formed from a single piece of resilient material having one end attached to a portion of itself, and having the other end bent to lie in opposition to the connected portion, and to be capable of a tensioned motion toward the connected portion. In some instances, it will be unnecessary to provide a guide lug 21 or a slot 22,

or their functional analogues shown as modified structures.

70 In the modification shown in Figure 7, the element 50 is turned in direction opposite to the element 29 and means to prevent separation of the elements 17-20 is provided. In this instance, this means comprises a screw 51 having its shank passing through the extension 50 and through a slot 57 in the element 10, along with a wing nut 52 in threaded engagement with the screw to clamp the parts against motion in direction of the arrow B. This clamp is made active only after the elements 17-20 have been attached in the usual manner by springing them apart.

75 All details of construction are included as features of the invention, along with the broader features, which are not intended to be limited by details.

80 I claim as my invention:

85 1. A bumper rack having a load-supporting portion, and opposed portions one of which is yieldable and adapted to move toward the other under tension to act as a clamp.

90 2. A bumper rack comprising a single piece of metal bent to provide a load-supporting portion, and opposed portions one of which is yieldable and adapted to move toward the other under tension to act as a clamp.

95 3. A bumper rack comprising a single piece of metal bent to substantially triangular form, and to provide two opposed portions which extend from one of the apices of the triangle across the same, and which lie substantially perpendicular to that side opposite the apex, one of said opposed portions being adapted to move toward the other under tension.

100 4. A bumper rack having a substantially triangular form, and having two opposed portions which extend from one of the apices of the triangle across the same and which lie substantially perpendicular to that side opposite the apex, one of said opposed portions being adapted to move toward the other under tension.

105 5. A bumper rack comprising a single piece of metal bent to provide a trussed structure including a load-supporting portion adapted to assume a substantially horizontal position when the device is attached, and to provide opposed portions one of which is yieldable and adapted to move toward the other under tension, said opposed portions being arranged in substantially perpendicular relation to the load-receiving portion.

110 6. A bumper rack comprising a single piece of metal bent to provide a trussed structure including a load-receiving portion adapted to assume a substantially horizontal position when the device is attached, and to provide opposed portions one of which is

yieldable and adapted to move toward the other under tension, said opposed portion being arranged in substantially perpendicular relation to the load-receiving portion, and
5 means for securing the opposed portions against separation after attachment to a bumper or support.

7. A bumper rack comprising a single piece of metal bent to substantially triangular form, and to provide two opposed portions which extend from one of the apices of the triangle across the same and which lie substantially perpendicular to that side opposite the apex, one of said opposed portions being adapted to move toward the other under tension and stop means for preventing deformation of the movable portion when attaching the rack and after attachment.

In witness whereof, I have hereunto set my hand this 24th day of April, 1930.

WILLIAM E. V. SHAW.
